UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPE OR MATRIX.

1,268,578.

Specification of Letters Patent. Patented June 4, 1918.

Application filed June 28, 1915. Serial No. 36,618.

To all whom it may concern:

Be it known that I, DAVID S. KENNEDY, a citizen of the United States, residing at Brooklyn, in the county of Kings and State 5 of New York, have invented certain new and useful Improvements in Type or Matrices, of which the following is a specification, reference being had therein to the accompanying drawing.

10 My invention relates to type or matrices for typographical machines, such as lino-type machines of the general organization represented in Letters Patent of the United States No. 436532, to O. Mergenthaler, 15 wherein circulating matrices are released from a magazine in the order in which their characters are to appear in print and then assembled in line, the composed line transferred to the face of a mold, the mold filled 20 with molten metal to form a slug or lino-type against the matrices which produce the type characters thereon, and the matrices thereafter returned through a distributing mechanism to the magazine from which they 25 started.

In such machines, the matrices are usually fed to the distributing mechanism by means 30 of a lifting finger, which raises them individually from the line past an overlying stop bar or rail which serves to prevent the detachment of more than one of them at a time. As the matrices of a font vary in thickness according to character, they are ordinarily provided at their upper ends with 35 longitudinal cuts or notches so as to straddle the stop rail during their individual detachment, such notches varying in depth according to the thickness of the matrices so as to leave portions of substantially uniform 40 thickness in all of them, whether large or small.

Heretofore, the notches just described have been formed by means of a rotary saw having a considerable radius, and they consequently acquire great extent in matrices of 45 substantial thickness, extending practically throughout their length and resulting in an appreciable weakening. This weakening becomes quite serious in connection with the 50 thicker matrices, and particularly those having "head-letter" or "display" characters, because the notches are not only necessarily of greater depth and length, but in addition such large matrices are commonly formed 55 with other longitudinal notches or grooves

to remove as much metal as possible to lighten them.

My present invention is intended to overcome the above objections, and aims to produce the matrices with separating notches of 60 only such extent as is necessary to allow them to clear the overlying stop rail during their detachment from the line, the notches thus being of small and uniform extent throughout the set or font and thereby 65 avoiding the weakening of the matrix bodies.

In the accompanying drawing, I have shown my invention in preferred form and by way of example, but obviously many variations and alterations may be made therein and in its mode of application without departure from its spirit. Generally speaking, I desire it to be understood that I do not limit myself to any specific form or 75 embodiment, except in so far as such limitations are specified in the claims.

Referring to the drawing:

Figure 1 is a rear view of a portion of the distributing mechanism of a linotype machine, illustrating the use of matrices constructed in accordance with my invention;

Fig. 2 is a perspective view of one of the matrices; and

Figs. 3 and 4 are sections on the lines 85 3-3 and 4-4 of Fig. 2, respectively.

The matrices X are of the usual rectangular form, containing in one edge the formative cavity or character X', and provided with the customary supporting ears X¹ and 90 the tooth combination X². After casting, the line of matrices is transferred through the distributing box A toward the lifting finger A¹, which elevates them one at a time and delivers them to the conveying 95 screws B¹, whereby they are carried along the guide rails A⁴ onto the distributor bar B, all in the usual way. Just prior to its detachment from the line, the leading matrix therein is arrested by an upstanding 100 shoulder A² which determines its proper location for engagement by the lifting finger A¹. As the matrix is raised by the finger, it passes by the overlying stop rail or bar A³, being provided with the vertical cut or 105 notch X³ to straddle the rail, the notch being of such depth as to leave a thin portion X⁴ at the front of the matrix, equal in thickness substantially to the horizontal distance between the shoulder A² and the rail 110

- 2
- A^s, and which thus clears the rail. It will be understood, of course, that the portions X^t are of uniform thickness in all the matrices, so as to allow them, irrespective of size or thickness, to pass by the rail A^s during their detachment from the line, and that consequently the notches X^s must vary in depth, depending upon the thickness of the matrix.
- 10 Heretofore the notches X^s have been of considerable length, due to the great radius of the cutting saw by which they were formed, and extended practically throughout the length of the thicker matrices, as represented by dotted lines in Fig. 1. As a result, the matrices were appreciably weakened, and particularly in that the necessary support was taken away from the front walls or edges of the matrices where-
- 20 in the formative characters are located, and further because there was the liability that the walls might sink or fall inwardly, causing the matrices to lose their proper rectangular form so that they would fail to lock up properly in the assembled line or fit closely against the mold when presented thereto. These objections are accentuated in the very large or thick matrices, wherein the notches are not only of great depth, but
- 30 wherein other notches or cuts, such as X^e shown in Figs. 2, 3 and 4, are made in the bodies to remove as much metal as possible for lightening purposes. Other objections are also present,—for instance, the notches
- 35 interfere with the formation of certain distributing notches which are located at the lower ends of the matrices of some fonts. Of course the above remarks apply principally to matrices of substantial thickness, as
- 40 obviously the depth of the notches X^s in the thinner ones will be negligible, and indeed they are entirely absent in the extremely thin matrices, such as hair spaces and the like.
- 45 It is the aim of my present invention to avoid the foregoing objections, and to this end, the notches X^s throughout the font are made of a uniform extent, corresponding approximately to the distance the matrices
- 50 are raised by the lifting finger A¹ during their detachment from the line. In this way, the matrices remain solid throughout the greater portion of their length, the notches terminating above the middle of the
- 55 matrix and well above the lowest point of its formative cavity X^t, as shown clearly in Fig. 2, thus affording a rigid or solid support behind the cavity and preventing the sinking of its containing wall. In short,
- 60 the presence of the notches as made in ac-

cordance with my invention, does not impair the strength of the matrices in any respect or allow them to lose their proper shape or form.

In the manufacture of my improved matrices, a hole X^s is first drilled through them from one side to the other, and the slot X^s is next cut outwardly from the hole by means of a suitable tool, such as a milling or planing tool or the like. An air blast is employed during the slotting process to blow off the chips, the hole X^s furnishing a good exit therefor and greatly facilitating the operation. This method not only allows the matrices to be made with notches of the short and uniform length described, but greatly simplifies and reduces the expense of their manufacture.

As previously stated, I have shown my invention only in preferred form and by way of example and as applied to a specific style of matrix. However, many modifications and alterations therein and in its mode of application will readily suggest themselves to those skilled in the art without departure from its scope.

Having thus described my invention, its construction and mode of operation, what I claim and desire to secure by Letters Patent of the United States, is as follows:

1. A set or font of type or matrices, some formed at their upper ends with separating slots or notches, the said notches being of uniform extent throughout the font.

2. A set or font of type or matrices, some formed at their upper ends with separating slots or notches, the said notches being of uniform extent throughout the font and terminating above the middle portions of the type or matrices.

3. A set or font of type or matrices, some formed at their upper ends with separating slots or notches, the said notches being of uniform extent throughout the font and terminating above the lowest points of the type or matrix characters.

4. A set or font of type or matrices, some formed at their upper ends with separating slots or notches, the said notches throughout the font being of uniform extent equal approximately to the distance the type or matrices are raised by the lifting finger of a distributor box in a linotype machine.

In testimony whereof, I have affixed my signature in presence of two witnesses.

DAVID S. KENNEDY.
